UNITED STATES PATENT OFFICE.

DAVID H. ALLEN, OF SULFUR, COLORADO.

WIRE STRETCHER.

1,410,523.

Specification of Letters Patent. Patented Mar. 21, 1922.

Application filed November 27, 1920. Serial No. 426,837.

To all whom it may concern:

Be it known that I, DAVID H. ALLEN, a citizen of the United States, residing at Sulfur, in the county of Rio Blanco, State 5 of Colorado, have invented new and useful Improvements in Wire Stretchers, of which the following is a specification.

It is the object of this invention to provide a wire stretcher of extremely simple 10 construction and adapted to be readily placed in operative position, and actuated for stretching a wire and then retaining the latter in its stretched condition.

The invention will be readily understood 15 from the following description of the accompanying drawings, in which:

Figure 1 is a plan view showing the wire stretcher applied to a wire.

Fig. 2 is a similar view after the wire has 20 been stretched and showing the stretcher in position for retaining the wire in its stretched condition.

Figs. 3 and 4 are end views of the wire stretcher with the latter in the positions 25 shown in Figs. 1 and 2 respectively.

Fig. 5 is a section on the line 5—5 of Fig. 3.

Fig. 6 is an end view of the wire stretcher taken from the opposite end from that 30 shown in Figs. 3 and 4.

The improved wire stretcher is an integral structure comprising a hub 1 having the disc 2 projecting from the same intermediate of its ends. The disc 2 is provided 35 with a peripheral flange 3 extending toward end 5 of the hub of the stretcher, and this flange is provided around its circumference with inclined notches 4.

The end 5 of the hub is transversely slot- 40 ted as shown at 6, said slot extending to a suitable depth within the hub, and the end 5 may also be provided with a peripheral beading 7 at its outer end. The junction of the end portion 5 of the hub with disc 2 45 also provides a peripheral beading 7^a. By this arrangement the end portion of the hub between the beadings forms a reel on which wire may be wound.

The opposite end of the hub shown at 8 50 is arranged as a head adapted to be received by a suitable socket wrench or crank

handle, and in the present embodiment of the invention this head is shown as a square head in cross section.

The wire to be stretched is shown at 10, 55 and in operation the stretcher is positioned with the wire received in the base of slot 6. The slot preferably extends to such a depth that its base is in alinement with disc 2, and the wire 10 is thereby positioned adjacent the flange 3. The head 8 is then engaged by a suitable handle or wrench, and is rotated so as to wind the wire 10 upon the reel formed by the stretcher, and as a consequence the wire is stretched. The 60 stretcher is rotated in the direction of inclination of notches 4, so that after the wire has been suitably stretched by engaging the ends thereof in notches of flange 3, reverse rotation of the stretcher will be prevented 65 by this engagement of the wire ends with in the notches. The stretcher is thus securely held against unwinding, and as a consequence the wire is maintained in its stretched condition. 75

If it is desired to subsequently release the wire, it is only necessary to axially shift the stretcher until the wire ends are disengaged from notches 4, so that the stretcher is free for reverse rotation. After the 80 stretcher is thus reversely rotated, it may be readily removed from the wire by removing the latter from slot 6.

Thus it will be seen that I have provided a wire stretcher readily attachable to and 85 removable from a wire, and arranged to provide for stretching the wire and retaining the latter in stretched condition.

Various changes may be made without departing from the spirit of the invention as 90 claimed.

What is claimed is:

1. A wire stretcher comprising a hub having a slotted end, means at the other end of said hub for rotating the same, and a disc 95 on said hub having inclined peripheral notches extending toward the slotted end of the hub.

2. A wire stretcher comprising a hub having a slotted end, and a disc on said hub 100 having a peripheral flange extending toward the slotted end of the hub, said flange hav-

ing circumferentially spaced inclined notches therein.

3. A wire stretcher comprising a hub having a slotted end, and a disc on said hub having a peripheral flange extending toward the slotted end of the hub, said flange having circumferentially spaced inclined

notches therein, the other end of said slotted hub and the junction of said hub with said disc forming peripheral beads on said hub arranged to provide a reel.

In testimony whereof I have signed my name to this specification.

DAVID H. ALLEN.
